(57) **CLAIM**

The ornamental design for a water dispensing system, as shown and described.

DESCRIPTION

FIG. 1 is a top perspective view of a water dispensing system, showing my design;

FIG. 2 is a bottom perspective view thereof;

FIG. 3 is a front view thereof;

FIG. 4 is a right side view thereof;

FIG. 5 is a back view thereof; and,

FIG. 6 is a top view thereof.

The broken lines shown in the drawings are included for the purpose of illustrating environmental structure and form no part of the claimed design.
